UNITED STATES PATENT OFFICE.

LEOPOLD JULIG, OF SAN FRANCISCO, CALIFORNIA.

GAS-LAMP.

SPECIFICATION forming part of Letters Patent No. 327,089, dated September 29, 1885.

Application filed July 7, 1885. (No model.)

To all whom it may concern:

Be it known that I, LEOPOLD JULIG, of the city and county of San Francisco, and State of California, have invented an Improvement 5 in Gas-Lamps; and I hereby declare the following to be a full, clear, and exact description thereof.

My invention relates to the class of gas or vapor lamps; and my invention consists in an 10 oil-reservoir having an outer chamber to which the oil is fed and an inner chamber communicating with the outer one, a peculiar burner communicating with the outer chamber, a rotating fan within the inner chamber above the 15 oil and operated by an electric current, a valved port communicating with the inner chamber, whereby air is drawn in by the fan, and in various details of construction, all of which I shall hereinafter fully explain.

20 The object of my invention is to provide an effective lamp for burning the gases or vapors originating from gasoline and other liquid hydrocarbons.

25 Referring to the accompanying drawings, Figure 1 is a vertical section of my gas-lamp, one portion of the reservoir being in elevation and broken away. Fig. 2 is a portion of a horizontal section through the reservoir R and fan.

30 R is an oil-reservoir, in which is formed an outer annular chamber, A, with which a supply-aperture, a, having a screw-cap, a', communicates.

B is an inner chamber in the reservoir, which 35 communicates with chamber A by means of an aperture, b.

C is the bracket by which the lamp is suspended. The portion c of the bracket is tubular and communicates with chamber A at its 40 lower end. At its upper end it communicates with a short pipe, c', into which the burner D is screwed. This burner is made of a central or inner open-ended pipe, d, for ventilation, and one or more encircling or outer pipes, d', which are so formed as to leave a larger annular chamber or space, d², below, and a 45 smaller annular chamber or space, d³, above.

E is the burner-key in the hollow stem e of the burner, which said stem communicates at 50 one end with the short pipe c', and at the other with the larger chamber or space d².

F is the cap-plate or top of the reservoir R. Through its center is a port, f, controlled by a valve, f', the upper portion of whose stem f² is guided by a cross-bar, G, and its lower portion, extending downwardly into the chamber B, carries the fan H, so that said stem forms the fan-shaft. The point or foot of the stem f² is stepped in the upper end of a screw, I, passing through a threaded socket in the 60 bottom of the reservoir, and vertically adjusted by means of a small crank, J, below.

Upon the cap-plate or top F is the electro-magnet L, the cores l of which pass down through the plate.

65 M are the circuit-wires of the magnet, to be connected with a battery and arranged so that the circuit will be closed and opened by the vertically-moving valve. Upon the fan are the armatures N of the magnets, arranged, 70 as shown, in a manner to effect the rotation of the fan when the circuit is closed by the upward adjustment of the screw I, which elevates the valve f' into contact with one of the circuit-wires. This adjustment at the same time opens 75 the port f.

Secured to the fan-blades are the downward- 80 extending arms or agitators O. The top of valve f' is a cam, so that the electric contact is momentarily broken to effect the rotation of the fan.

85 The operation of the lamp is as follows: Gasoline or other suitable liquid hydrocarbon is supplied to the chamber A through aperture a, and it rises in both chambers A and B to the level of the base of the supply-aperture, which is so located that the fan H is just above the level of the oil. The screw I is set up to raise the valve f' slightly and close the electric circuit, and at the same time, by raising said valve, 90 to open the port f. The fan is rotated by the action of the electric current, whereby the air is drawn in through the open port f, and forced by the fan through the aperture b into chamber A. This air travels around nearly the whole 95 circumference of chamber A, mixing thoroughly with the gasoline, and the vapors ascend through tube e and into the burner. Here the gas collects in the lower and larger chamber, d², and feeds the flame in sufficient quantities at the top of the upper and smaller chamber, d³.

The agitators O keep the oil in motion, and tend to a more thorough mixture of air and gasoline.

It will be observed, Fig. 2, that though the 5 aperture b, through which the air passes into the chamber A, is near the exit-tube c of said chamber, it is not directly in communication therewith, so that the air has to pass around nearly the entire circumference of the chamber 10 A before reaching the exit. This is for the purpose of causing it to mix thoroughly with the gasoline.

The object of the larger chamber d² in the 15 base of the burner is to provide for an accumulation of gas to keep up the combustion above. I have found that if the chamber in the burner is the same size all the way down the feed is not regular or constant; but by accumulating in the lower chamber the flame is 20 steady.

To turn off the light, the key E is used, and to throw the lamp completely out of operation the screw I is lowered, whereby the fan drops down and opens the circuit, and at the same 25 time the valve f' closes the port f.

Having thus described my invention, what I claim as new, and desire to secure by Letters Patent, is—

1. In a gas-lamp, the combination of an oil 30 chamber or reservoir, a burner communicating therewith, a rotating fan, suitable armatures on the fan, and an electro-magnet for operating the fan, substantially as and for the purpose described.

2. In a gas-lamp, the combination of the 35 oil-reservoir R, having an outer chamber, A, and an inner chamber, B, with a communicating aperture, b, a burner, a pipe communicating with the burner and with the outer 40 chamber, A, the latter communication or exit being as far as possible from the aperture or entrance between the two chambers, and a rotating fan in the inner chamber above the oil, substantially as herein described.

3. In a gas-lamp, the combination of the oil-reservoir R, having an outer chamber, A, with 45 a supply-aperture, and an inner chamber, B, with an aperture communicating with chamber A, a burner communicating with the outer chamber, a rotating fan in the inner chamber above the oil, and a valved port in the top of the reservoir through which the air is drawn by the rotating fan, substantially as described.

4. In a gas-lamp, the combination of the oil-reservoir R, having a port, f, an inner chamber, B, with which the port communicates, and an outer chamber, A, communicating 50 with chamber B, a burner communicating 60 with the outer chamber, a vertically-moving valve controlling the port f, having stem f², the fan H on the stem, and the vertically-ad-

justable screw I through the bottom of the reservoir, in which the valve-stem is stepped, substantially as described.

65

5. In a gas-lamp, the combination of the oil-reservoir R, having an outer chamber, A, with a supply aperture, and an inner chamber, B, having an aperture, b, communicating with chamber A, a burner communicating with the outer chamber, the fan H in the inner chamber, and the mechanism for rotating said fan, consisting of the electro-magnet L on the reservoir, an electric circuit including the magnet, and the armatures N on the fan, substantially as described.

70

6. In a gas-lamp, the combination of the oil-reservoir R, having an outer chamber, A, with a supply-aperture, and an inner chamber, B, having an aperture, b, communicating with chamber A, and a top port, f, a burner communicating with the outer chamber, the valve f', controlling the port and having stem f², the fan H on the stem, the adjusting screw I, in which the stem is stepped, the electro-magnet L in a battery - circuit closed and opened by the valve, and the armatures N on the fan, all arranged and adapted to operate substantially as herein described.

80

7. In a gas-lamp, the combination of the oil-reservoir R, having concentric communicating chambers A and B, the supporting-bracket C, one arm, c, of which is tubular and communicates with chamber A, the burner D, supported from the bracket and communicating with the tubular arm c, and the rotating fan H in chamber B above the oil, substantially as described.

90

8. In a gas-lamp, the combination of the oil-reservoir R, the burner D, communicating therewith, the rotating fan in the reservoir above the oil, and adapted to draw in air and force it into the oil, and the agitator-arms O on the fan extending down into the oil, substantially as herein described.

100

9. A gas-lamp comprising the reservoir R, having concentric communicating chambers A B, the burner D, communicating by pipe c with the chamber A, the vertically-adjustable valve f', controlling an air-port in the top of chamber B, the rotating fan H on the valve-stem and above the oil in chamber B, the agitator-arms on said fan and extending into the oil, the electro-magnet L, and circuit-wires on the reservoir, and the armatures N on the fan, whereby it is rotated, substantially as described.

105

In witness whereof I have hereunto set my hand.
